(57) **ABSTRACT**

A non-common-ground bandpass filter circuit with electrostatic discharge (ESD) protection is disclosed. The non-common-ground bandpass filter circuit with ESD protection includes a non-common-ground plane, a dielectric substrate and a conductor. The conductor is disposed above the non-common-ground plane. The dielectric substrate is disposed between the conductor and the non-common-ground plane. The non-common-ground plane at least has a first ground region and a second ground region separated and insulated from each other. The first ground region corresponds to a first terminal of the conductor and the second ground region corresponds to a second terminal of the conductor. When an ESD event occurs on one of the first ground region and the second ground region, the other of the first ground region and the second ground region will not be damaged by the ESD event. The non-common-ground bandpass filter circuit also provides surge protection.

**NON-COMMON-GROUND BANDPASS
FILTER CIRCUIT WITH ELECTROSTATIC
DISCHARGE PROTECTION**

**CROSS REFERENCE TO RELATED
APPLICATION**

This non-provisional application claims the benefit under 35 U.S.C. § 119(e) to U.S. Provisional Application No. 62/892,693, filed on Aug. 28, 2019, which is hereby expressly incorporated by reference into the present application.

FIELD OF THE INVENTION

The invention relates to a bandpass filter circuit, and specifically to a non-common-ground bandpass filter circuit with electrostatic discharge (ESD) protection.

BACKGROUND OF THE INVENTION

Microstrip is a type of electrical transmission line which can be fabricated using printed circuit board technology, and is used to convey microwave-frequency signals. It consists of a conducting strip separated from a ground plane by a dielectric layer known as the substrate. Microwave components such as antennas, couplers, filters, power dividers etc. can be formed from microstrip, with the entire device existing as the pattern of metallization on the substrate. Microstrip is thus much less expensive than traditional waveguide technology, as well as being far lighter and more compact. The disadvantages of microstrip compared with waveguide are the generally lower power handling capacity and higher losses. Also, unlike waveguide, microstrip is not enclosed, and is therefore susceptible to cross-talk and unintentional radiation.

Please refer to FIG. 1A and FIG. 1B. FIG. 1A illustrates a schematic view of a conventional bandpass filter circuit and FIG. 1B illustrates simulation results of the conventional bandpass filter circuit shown in FIG. 1A.

As shown in FIG. 1A, in the conventional bandpass filter circuit 1, a conductor is disposed above a common-ground plane 10 to form a microstrip structure 12 and a dielectric substrate (e.g., a FR-4 substrate) is disposed between the microstrip structure 12 and the common-ground plane 10.

Please refer to FIG. 2. FIG. 2 illustrates a simulation circuit diagram of the conventional bandpass filter circuit 1 shown in FIG. 1A. As shown in FIG. 2, the microstrip cross junction MCROSO is coupled to the resistor Term through the microstrip line MLIN and coupled to the microstrip short-circuited stub MLSC; two microstrip cross junctions MCROSO are coupled through the microstrip line MLIN.

Please refer to FIG. 3. FIG. 3 illustrates a schematic view of the simulated S-parameters of the conventional bandpass filter circuit 1 shown in FIG. 1A. As shown in FIG. 3, m1 represents $dB(S(4,3)) = -0.308$ at the frequency of 2.4 GHz; m2 represents $dB(S(4,3)) = -0.316$ at the frequency of 2.5 GHz; m3 represents $dB(S(4,3)) = -0.650$ at the frequency of 5.2 GHz; m4 represents $dB(S(4,3)) = -0.772$ at the frequency of 5.801 GHz.

However, since the entire common-ground plane 10 in the conventional bandpass filter circuit 1 is electrically connected, as shown in the simulation results of FIG. 1B, when an electrostatic discharge (ESD) event occurs, the conventional bandpass filter circuit 1 fails to provide any ESD

2

protection, so that the circuits coupled to the conventional bandpass filter circuit 1 will be damaged by the ESD event.

SUMMARY OF THE INVENTION

In light of the above, one of the objectives of the invention is to provide a non-common-ground bandpass filter circuit with electrostatic discharge (ESD) protection.

An embodiment of the invention is a non-common-ground bandpass filter circuit with ESD protection. In this embodiment, the non-common-ground bandpass filter circuit with ESD protection includes a non-common-ground plane, a dielectric substrate and a conductor. The conductor is disposed above the non-common-ground plane. The dielectric substrate is disposed between the conductor and the non-common-ground plane. The non-common-ground plane at least has a first ground region and a second ground region. The first ground region and the second ground region are separated and insulated from each other. The first ground region and the second ground region correspond to a first terminal and a second terminal of the conductor respectively.

In an embodiment of the invention, when an ESD event occurs on one of the first ground region and the second ground region, the other of the first ground region and the second ground region is not damaged by the ESD event, and the non-common-ground bandpass filter circuit also provides surge protection.

In an embodiment of the invention, shapes of the first ground region and the second ground region are complementary to each other.

In an embodiment of the invention, the non-common-ground plane has a defected ground structure (DGS) to form the first ground region and the second ground region separated and insulated from each other.

In an embodiment of the invention, the DGS includes a slot disposed on the non-common-ground plane.

In an embodiment of the invention, the slot has a linear shape or a polyline shape.

In an embodiment of the invention, the slot is disposed along a length direction of the non-common-ground plane.

In an embodiment of the invention, the slot is disposed along a width direction of the non-common-ground plane.

In an embodiment of the invention, some parts of the slot are disposed along a length direction of the non-common-ground plane and the other parts of the slot are disposed along a width direction of the non-common-ground plane.

In an embodiment of the invention, the DGS further includes at least one space disposed between the first ground region and the second ground region and connected to the slot.

In an embodiment of the invention, a width of the space is larger than a width of the slot.

In an embodiment of the invention, the non-common-ground plane has arbitrary geometry.

In an embodiment of the invention, a microstrip structure is formed by the conductor.

In an embodiment of the invention, the microstrip structure includes a microstrip transmission line, a first terminal and a second terminal of the microstrip transmission line are disposed above the first ground region and the second ground region respectively.

In an embodiment of the invention, the microstrip structure further includes at least one microstrip antenna electrically connected to the microstrip transmission line.

In an embodiment of the invention, the microstrip antenna has a first portion and a second portion electrically connected to each other.

In an embodiment of the invention, the first portion of the microstrip antenna is electrically connected to the microstrip transmission line and vertical to a length direction of the microstrip transmission line.

In an embodiment of the invention, the second portion of the microstrip antenna is electrically connected to the first portion and parallel to the length direction of the microstrip transmission line.

In an embodiment of the invention, a size of the non-common-ground plane is changed by adjusting a length of the first ground region or the second ground region.

In an embodiment of the invention, a size of the non-common-ground plane is changed by adjusting a width of the first ground region or the second ground region.

Compared to the prior art, the non-common-ground bandpass filter circuit with ESD protection of the invention has a non-common-ground plane including at least two ground regions separated and insulated from each other by a defect ground structure such as a slot or a space, so that when an ESD event occurs on one ground region, the other ground region(s) will not be damaged by the ESD event. Therefore, the non-common-ground bandpass filter circuit with ESD protection of the invention can provide better ESD protection function than the common-ground bandpass filter circuit of the prior art. In addition, the non-common-ground bandpass filter circuit of the invention can also provide good surge protection function.

To further learn the features and technical content of the invention, please refer to the following detailed descriptions and drawings related to the invention. However, the provided drawings are used only for providing reference and descriptions, and are not intended to limit the invention.

BRIEF DESCRIPTION OF THE DRAWINGS

FIG. 49A illustrates a schematic view of 72.5 mm*40 mm non-common-ground bandpass filter circuit with a defected

ground plane (Type 2) having one polyline narrow (0.2 mm) slot disposed near the upper side, wherein the size of the ground plane is changed, and some parts of the narrow (0.2 mm) polyline slot disposed along the width direction and the other parts of the narrow (0.2 mm) polyline slot disposed along the length direction.

FIG. 49B illustrates simulation results of FIG. 49A.

DETAILED DESCRIPTION OF THE PREFERRED EMBODIMENTS

An embodiment of the invention is a non-common-ground bandpass filter circuit with ESD protection. In this embodiment, the non-common-ground bandpass filter circuit with ESD protection can include a non-common-ground plane, a dielectric substrate and a conductor. The conductor is disposed above the non-common-ground plane to form a microstrip structure. The dielectric substrate is disposed between the conductor and the non-common-ground plane.

The non-common-ground plane at least has a first ground region and a second ground region separated and insulated from each other. The first ground region and the second ground region correspond to a first terminal and a second terminal of the conductor respectively. The shapes of the first ground region and the second ground region are complementary to each other. When an ESD event occurs on one of the first ground region and the second ground region, the other of the first ground region and the second ground region is not damaged by the ESD event.

Please refer to FIG. 4A and FIG. 4B. FIG. 4A illustrates a schematic view of a non-common-ground bandpass filter circuit with ESD protection in an embodiment of the invention; FIG. 4B illustrates simulation results of the non-common-ground bandpass filter circuit with ESD protection shown in FIG. 4A.

As shown in FIG. 4A, in a non-common-ground bandpass filter circuit with ESD protection 2, a microstrip structure 22 including a microstrip transmission line 22A and microstrip antennas 22B is formed by a conductor disposed above the non-common-ground plane 20. The dielectric substrate (not shown) is disposed between the microstrip structure 22 and the non-common-ground plane 20. The microstrip antennas 22B can be coupled to the ground through the via, but not limited to this. In this embodiment, the length of the non-common-ground plane 20 is 28.6 mm and the width of the non-common-ground plane 20 is 20 mm, the size of the non-common-ground plane 20 is 28.6 mm*20 mm and the width of the microstrip antennas 22B is 0.3 mm, but not limited to this.

It should be noticed that the non-common-ground plane 20 has a first ground region 20A and a second ground region 20B. The first ground region 20A and the second ground region 20B are separated from each other by a narrow slot 24. And, the first ground region 20A and the second ground region 20B are insulated from each other.

It can be found that the shapes of the first ground region 20A and the second ground region 20B are complementary to each other. The first ground region 20A is disposed near the upper side of the non-common-ground plane 20 and the second ground region 20B is disposed near the lower side of the non-common-ground plane 20. The area of the first ground region 20A is smaller than the area of the second ground region 20B.

Since a first terminal T1 of the microstrip transmission line 22A is disposed above the upper side of the non-common-ground plane 20 and a second terminal T2 of the microstrip transmission line 22A is disposed above the lower

side of the non-common-ground plane **20**, it is believed that the first ground region **20A** corresponds to the first terminal **T1** of the microstrip transmission line **22A** disposed above the upper side of the non-common-ground plane **20** and the second ground region **20B** corresponds to the second terminal **T2** of the microstrip transmission line **22A** disposed above the lower side of the non-common-ground plane **20**.

Since the first ground region **20A** and the second ground region **20B** of the non-common-ground plane **20** are separated and insulated from each other, when an ESD event occurs on one of the first ground region **20A** and the second ground region **20B** of the non-common-ground plane **20**, the other of the first ground region **20A** and the second ground region **20B** of the non-common-ground plane **20** will not be damaged by the ESD event.

After comparing the curve in FIG. 4B with the curve in FIG. 1B, it can be found that when the frequency is 2-3 GHz, the curve in FIG. 4B is not dropped so deep as the curve in FIG. 1B; that is to say, the drop of the curve caused by the ESD event in the conventional bandpass filter circuit **1** can be obviously improved by the non-common-ground bandpass filter circuit with ESD protection **2** shown in FIG. 4A.

Therefore, according to the simulation results of FIG. 4B, it can be said that the non-common-ground bandpass filter circuit with ESD protection **2** in this embodiment can provide well ESD protection for the circuits electrically connected to it, so that the non-common-ground bandpass filter circuit with ESD protection **2** of the invention can obviously improve the poor ESD protection of the conventional bandpass filter circuit **1** in the prior art.

Then, please refer to FIG. 5A to FIG. 5F. As shown in FIG. 5A to FIG. 5F, the non-common-ground plane can have arbitrary geometry without specific limitations; the shapes of the separated first ground region and second ground region of the non-common-ground plane are complementary to each other.

As shown in FIG. 6A, an interdigital slot **SL** is disposed on a 100 mm*100 mm non-common-ground plane **GP** and the height of the interdigital slot **SL** is 10 mm; a transmission line **TL** is disposed above the non-common-ground plane **GP**. And, FIG. 6B illustrates simulation results of FIG. 6A.

As shown in FIG. 7A, a narrow slot **SL** is disposed on a 100 mm*100 mm non-common-ground plane **GP** and the width of the narrow slot **SL** is 0.2 mm; a transmission line **TL** is disposed above the non-common-ground plane **GP**. And, FIG. 7B illustrates simulation results of FIG. 7A.

As shown in FIG. 8A, a wide slot **SL** is disposed on a 100 mm*100 mm non-common-ground plane **GP** and the width of the narrow slot **SL** is 9.8 mm; a transmission line **TL** is disposed above the non-common-ground plane **GP**. And, FIG. 8B illustrates simulation results of FIG. 8A.

As shown in FIG. 9A, an interdigital slot **SL** is disposed on a 50 mm*50 mm non-common-ground plane **GP** and the height of the interdigital slot **SL** is 10 mm, that is to say, the height of the interdigital slot **SL** of FIG. 9A is the same with the height of the interdigital slot **SL** of FIG. 6A, but the size of the non-common-ground plane **GP** of FIG. 9A is smaller than the size of the non-common-ground plane **GP** of FIG. 6A; a transmission line **TL** is disposed above the non-common-ground plane **GP**. And, FIG. 9B illustrates simulation results of FIG. 9A.

As shown in FIG. 10A, an interdigital slot **SL** is disposed on a 50 mm*50 mm non-common-ground plane **GP** and the height of the interdigital slot **SL** is 4 mm, that is to say, the size of the non-common-ground plane **GP** of FIG. 10A is the same with the size of the non-common-ground plane **GP** of FIG. 9A, but the height of the interdigital slot **SL** of FIG.

10A is smaller than the height of the interdigital slot **SL** of FIG. 9A. And, FIG. 10B illustrates simulation results of FIG. 10A.

As shown in FIG. 11A, an interdigital slot **SL** is disposed on a 50 mm*50 mm non-common-ground plane **GP** and the height of the interdigital slot **SL** is 2 mm, that is to say, the size of the non-common-ground plane **GP** of FIG. 11A is the same with the size of the non-common-ground plane **GP** of FIG. 10A, but the height of the interdigital slot **SL** of FIG. 11A is smaller than the height of the interdigital slot **SL** of FIG. 10A. And, FIG. 11B illustrates simulation results of FIG. 11A.

As shown in FIG. 12A, an interdigital slot **SL** is disposed on a 50 mm*50 mm non-common-ground plane **GP** and the height of the interdigital slot **SL** is 1 mm, that is to say, the size of the non-common-ground plane **GP** of FIG. 12A is the same with the size of the non-common-ground plane **GP** of FIG. 11A, but the height of the interdigital slot **SL** of FIG. 12A is smaller than the height of the interdigital slot **SL** of FIG. 11A. And, FIG. 12B illustrates simulation results of FIG. 12A.

As shown in FIG. 13A, a narrow slot **SL** is disposed on a 50 mm*50 mm non-common-ground plane **GP** and the width of the narrow slot **SL** is 0.2 mm; a transmission line **TL** is disposed above the non-common-ground plane **GP**. And, FIG. 13B illustrates simulation results of FIG. 13A.

As shown in FIG. 14A, the non-common-ground bandpass filter circuit has a 46 mm*50 mm defected ground plane (Type 1) **GP** having a narrow slot **SL** (width=0.2 mm); the transmission line **TL** and the antenna **AN** are disposed above the non-common-ground plane **GP**. The antenna **AN** can be coupled to the ground through the via, but not limited to this. And, FIG. 14B illustrates simulation results of FIG. 14A.

As shown in FIG. 15A, the non-common-ground bandpass filter circuit has a 46 mm*50 mm defected ground plane (Type 2) **GP** having a wide space **SP** (width=5 mm) and a narrow slot **SL** (width=0.2 mm) which are connected; the transmission line **TL** and the antenna **AN** are disposed above the non-common-ground plane **GP**. The antenna **AN** can be coupled to the ground through the via, but not limited to this. And, FIG. 15B illustrates simulation results of FIG. 15A.

As shown in FIG. 16A, the non-common-ground bandpass filter circuit has a 46 mm*50 mm defected ground plane (Type 3) **GP** having a narrow slot **SL** (width=0.4 mm) and two round spaces (diameter=7 mm) which are connected through the narrow slot **SL**. The antenna **AN** can be coupled to the ground through the via, but not limited to this. And, FIG. 16B illustrates simulation results of FIG. 16A.

As shown in FIG. 17A, the non-common-ground bandpass filter circuit has a 46 mm*50 mm defected ground plane (Type 4) **GP** having a narrow slot **SL** (width=0.2 mm) and two rectangle spaces (size=10 mm*5 mm) which are connected through the narrow slot **SL**. The antenna **AN** can be coupled to the ground through the via, but not limited to this. And, FIG. 17B illustrates simulation results of FIG. 17A.

As shown in FIG. 18A, the non-common-ground bandpass filter circuit has a 46 mm*50 mm defected ground plane (Type 4) **GP** having a narrow slot **SL** (width=0.2 mm) and two rectangle spaces (size=15 mm*5 mm) which are connected through the narrow slot **SL**. The antenna **AN** can be coupled to the ground through the via, but not limited to this. And, FIG. 18B illustrates simulation results of FIG. 18A.

As shown in FIG. 19A, the non-common-ground bandpass filter circuit has a 46 mm*50 mm defected ground plane (Type 4) **GP** having a narrow slot **SL** (width=0.2 mm) and two rectangle spaces (size=10 mm*5 mm) which are connected through the narrow slot **SL**. The antenna **AN** can be

11

coupled to the ground through the via, but not limited to this. And, FIG. 19B illustrates simulation results of FIG. 19A.

As shown in FIG. 20A, the non-common-ground band-pass filter circuit has a 46 mm*50 mm defected ground plane (Type 4) GP having a narrow slot SL (width=0.2 mm) and two rectangle spaces (size=5 mm*5 mm) which are connected through the narrow slot SL. The antenna AN can be coupled to the ground through the via, but not limited to this. And, FIG. 20B illustrates simulation results of FIG. 20A.

As shown in FIG. 21A, the non-common-ground band-pass filter circuit has a 40 mm*20 mm defected ground plane (Type 1) GP having a narrow slot SL (width=0.2 mm) and one rectangle space (size=5 mm*10 mm) which are connected. The antenna AN can be coupled to the ground through the via SHVIA, but not limited to this. And, FIG. 21B illustrates simulation results of FIG. 21A.

As shown in FIG. 22A, the non-common-ground band-pass filter circuit has a 40 mm*20 mm defected ground plane (Type 2) GP having a narrow slot SL (width=0.2 mm), one rectangle space (size=2.5 mm*5 mm) and one square space (size=5 mm*5 mm), wherein the rectangle space (2.5 mm*5 mm) and the square space (5 mm*5 mm) are connected through the narrow slot SL. The antenna AN can be coupled to the ground through the via, but not limited to this. And, FIG. 22B illustrates simulation results of FIG. 22A.

As shown in FIG. 23A, the non-common-ground band-pass filter circuit has a 40 mm*20 mm defected ground plane (Type 3) GP having a narrow slot (width=0.2 mm) SL, one rectangle space (size=5 mm*10 mm) and one square space (size=5 mm*5 mm), wherein the narrow slot SL and the rectangle space (size=5 mm*10 mm) are connected through the square space (size=5 mm*5 mm). The antenna AN can be coupled to the ground through the via, but not limited to this. And, FIG. 23B illustrates simulation results of FIG. 23A.

As shown in FIG. 24A, only one narrow slot SL (width=0.2 mm) is disposed on the center of a 40 mm*20 mm defected ground plane (Type 4) GP along the length direction of the defected ground plane GP. The antenna AN can be coupled to the ground through the via, but not limited to this. And, FIG. 24B illustrates simulation results of FIG. 24A.

As shown in FIG. 25A, two narrow slots SL (width=0.2 mm) are disposed on two sides of a 40 mm*20 mm defected ground plane (Type 5) GP along the length direction of the defected ground plane GP. The antenna AN can be coupled to the ground through the via, but not limited to this. And, FIG. 25B illustrates simulation results of FIG. 25A.

As shown in FIG. 26A, two narrow slots SL (width=0.2 mm) are disposed on two sides of a 40 mm*20 mm defected ground plane (Type 6) GP along the length direction of the defected ground plane GP, wherein a right-angle slot is connected with one terminal of each narrow slot SL. The antenna AN can be coupled to the ground through the via, but not limited to this. And, FIG. 26B illustrates simulation results of FIG. 26A.

As shown in FIG. 27A, two narrow slots SL (width=0.2 mm) are disposed on two sides of a 40 mm*20 mm defected ground plane (Type 7) GP along the length direction of the defected ground plane, wherein a right-angle slot is connected with one terminal of each narrow slot SL. The antenna AN can be coupled to the ground through the via, but not limited to this. And, FIG. 27B illustrates simulation results of FIG. 27A.

As shown in FIG. 28A, two narrow slots SL (width=0.2 mm) are disposed on two sides of a 40 mm*20 mm defected ground plane (Type 8) GP along the length direction of the

12

defected ground plane GP, wherein a linear slot is connected with one terminal of each narrow slot SL. The antenna AN can be coupled to the ground through the via, but not limited to this. And, FIG. 28B illustrates simulation results of FIG. 28A.

As shown in FIG. 29A, a narrow slot SL (width=0.2 mm) is disposed on one side of a 40 mm*20 mm defected ground plane (Type 9) GP along the length direction of the defected ground plane GP. The antenna AN can be coupled to the ground through the via, but not limited to this. And, FIG. 29B illustrates simulation results of FIG. 29A.

As shown in FIG. 30A, two narrow slots SL (width=0.2 mm) are disposed on two sides of a 25.6 mm*20 mm defected ground plane (Type 1) GP along the width direction of the defected ground plane GP, wherein a distance between the upper side/the lower side of the defected ground plane GP and the narrow slot SL is 7 mm. The antenna AN can be coupled to the ground through the via, but not limited to this. And, FIG. 30B illustrates simulation results of FIG. 30A.

As shown in FIG. 31A, two narrow slots SL (width=0.2 mm) are disposed on two sides of a 25.6 mm*20 mm defected ground plane (Type 1) GP along the width direction of the defected ground plane GP, wherein a distance between the upper side/the lower side of the defected ground plane GP and the narrow slot SL is 5 mm. The antenna AN can be coupled to the ground through the via, but not limited to this. And, FIG. 31B illustrates simulation results of FIG. 31A.

As shown in FIG. 32A, two narrow slots SL (width=0.2 mm) are disposed on two sides of a 25.6 mm*20 mm defected ground plane (Type 1) GP along the width direction of the defected ground plane GP, wherein a distance between the upper side/the lower side of the defected ground plane GP and the narrow slot SL is 3.5 mm. The antenna AN can be coupled to the ground through the via, but not limited to this. And, FIG. 32B illustrates simulation results of FIG. 32A.

As shown in FIG. 33A, two narrow polyline slots SL (width=0.2 mm) are disposed on two sides of a 25.6 mm*20 mm defected ground plane (Type 2) GP, wherein some parts 40 of the narrow polyline slot SL are disposed along the width direction of the defected ground plane GP and the other parts 45 of the narrow polyline slot SL are disposed along the length direction of the defected ground plane GP. The antenna AN can be coupled to the ground through the via, but not limited to this. And, FIG. 33B illustrates simulation results of FIG. 33A.

As shown in FIG. 34A, one narrow slot SL (width=0.2 mm) is disposed on one side near the upper side of a 25.6 mm*20 mm defected ground plane (Type 3) GP along the width direction of the defected ground plane GP. The antenna AN can be coupled to the ground through the via, but not limited to this. And, FIG. 34B illustrates simulation results of FIG. 34A.

As shown in FIG. 35A, one polyline narrow slot SL 55 (width=0.2 mm) is disposed on one side near the upper side of a 28.6 mm*20 mm defected ground plane (Type 4) GP, wherein some parts of the narrow polyline slot SL are disposed along the width direction of the defected ground plane GP and the other parts of the narrow polyline slot SL 60 are disposed along the length direction of the defected ground plane GP. The antenna AN can be coupled to the ground through the via, but not limited to this. And, FIG. 35B illustrates simulation results of FIG. 35A.

As shown in FIG. 36A, one polyline narrow slot SL 65 (width=0.2 mm) is disposed on a (28.6 mm+20 mm)*20 mm defected ground plane (Type 5) GP, wherein the size of the ground plane is changed, and some parts of the narrow

15

ground through the via, but not limited to this. And, FIG. 47D illustrates simulation results of FIG. 47C.

As shown in FIG. 48A, one linear narrow slot SL (width=0.2 mm) is disposed near the upper side of a 72.5 mm*40 mm defected ground plane (Type 1) GP along the length direction of the defected ground plane GP. The antenna AN can be coupled to the ground through the via, but not limited to this. And, FIG. 48B illustrates simulation results of FIG. 48A.

As shown in FIG. 49A, one polyline narrow slot SL (width=0.2 mm) is disposed near the upper side of a 72.5 mm*40 mm defected ground plane (Type 2) GP, wherein the size of the ground plane is changed, and some parts of the narrow polyline slot SL are disposed along the width direction of the defected ground plane GP and the other parts of the narrow polyline slot SL are disposed along the length direction of the defected ground plane GP. The antenna AN can be coupled to the ground through the via, but not limited to this. And, FIG. 49B illustrates simulation results of FIG. 49A.

Compared to the prior art, the non-common-ground bandpass filter circuit with ESD protection of the invention has a non-common-ground plane including at least two ground regions separated and insulated from each other by a defect ground structure such as a slot or a space, so that when an ESD event occurs on one ground region, the other ground region(s) will not be damaged by the ESD event. Therefore, the non-common-ground bandpass filter circuit with ESD protection of the invention can provide better ESD protection function than the common-ground bandpass filter circuit of the prior art. In addition, the non-common-ground bandpass filter circuit of the invention can also provide good surge protection function.

The present invention has been described with reference to the above embodiments, but the above embodiments are merely examples for implementing the present invention. It should be noted that the disclosed embodiments are not intended to limit the scope of the present invention. On the contrary, any modification and equivalent configuration within the spirit and scope of the appended claims shall fall within the scope of the present invention.

What is claimed is:

1. A non-common-ground bandpass filter circuit with electrostatic discharge (ESD) protection, comprising: a non-common-ground plane; a conductor, disposed above the non-common-ground plane; and a dielectric substrate, disposed between the conductor and the non-common-ground plane; wherein the non-common-ground plane at least has a first ground region and a second ground region separated and insulated from each other; the first ground region and the second ground region correspond to a first terminal and a second terminal of the conductor respectively; the non-common-ground plane has a defected ground structure (DGS) to form the first ground region and the second ground region separated and insulated from each other.
2. The non-common-ground bandpass filter circuit with ESD protection of claim 1, wherein when an ESD event occurs on one of the first ground region and the second ground region, the other of the first ground region and the second ground region is not damaged by the ESD event, and the non-common-ground bandpass filter circuit also provides surge protection.

16

3. The non-common-ground bandpass filter circuit with ESD protection of claim 1, wherein shapes of the first ground region and the second ground region are complementary to each other.
4. The non-common-ground bandpass filter circuit with ESD protection of claim 1, wherein the DGS comprises a slot disposed on the non-common-ground plane.
5. The non-common-ground bandpass filter circuit with ESD protection of claim 4, wherein the slot has a linear shape or a polyline shape.
6. The non-common-ground bandpass filter circuit with ESD protection of claim 4, wherein the slot is disposed along a length direction of the non-common-ground plane.
7. The non-common-ground bandpass filter circuit with ESD protection of claim 4, wherein the slot is disposed along a width direction of the non-common-ground plane.
8. The non-common-ground bandpass filter circuit with ESD protection of claim 4, wherein some parts of the slot are disposed along a length direction of the non-common-ground plane and the other parts of the slot are disposed along a width direction of the non-common-ground plane.
9. The non-common-ground bandpass filter circuit with ESD protection of claim 4, wherein the DGS further comprises at least one space disposed between the first ground region and the second ground region and connected to the slot.
10. The non-common-ground bandpass filter circuit with ESD protection of claim 9, wherein a width of the space is larger than a width of the slot.
11. The non-common-ground bandpass filter circuit with ESD protection of claim 1, wherein the non-common-ground plane has arbitrary geometry.
12. The non-common-ground bandpass filter circuit with ESD protection of claim 1, wherein a microstrip structure is formed by the conductor.
13. The non-common-ground bandpass filter circuit with ESD protection of claim 12, wherein the microstrip structure comprises a microstrip transmission line, a first terminal and a second terminal of the microstrip transmission line are disposed above the first ground region and the second ground region respectively.
14. The non-common-ground bandpass filter circuit with ESD protection of claim 13, wherein the microstrip structure further comprises at least one microstrip antenna electrically connected to the microstrip transmission line.
15. The non-common-ground bandpass filter circuit with ESD protection of claim 14, wherein the microstrip antenna has a first portion and a second portion electrically connected to each other.
16. The non-common-ground bandpass filter circuit with ESD protection of claim 15, wherein the first portion of the microstrip antenna is electrically connected to the microstrip transmission line and vertical to a length direction of the microstrip transmission line.
17. The non-common-ground bandpass filter circuit with ESD protection of claim 16, wherein the second portion of the microstrip antenna is electrically connected to the first portion and parallel to the length direction of the microstrip transmission line.
18. The non-common-ground bandpass filter circuit with ESD protection of claim 1, wherein a size of the non-common-ground plane is changed by adjusting a length of the first ground region or the second ground region.
19. The non-common-ground bandpass filter circuit with ESD protection of claim 1, wherein a size of the non-common-ground plane is changed by adjusting a width of the first ground region or the second ground region.

20. A non-common-ground bandpass filter circuit with ESD protection, comprising:

- a non-common-ground plane;
- a conductor, disposed above the non-common-ground plane; and
- a dielectric substrate, disposed between the conductor and the non-common-ground plane;

wherein the non-common-ground plane at least has a first ground region and a second ground region separated and insulated from each other; the first ground region ⁵ ₁₀ and the second ground region correspond to a first terminal and a second terminal of the conductor respectively; a microstrip structure is formed by the conductor; the microstrip structure comprises a microstrip transmission line, a first terminal and a second terminal ₁₅ of the microstrip transmission line are disposed above the first ground region and the second ground region respectively.
